UNITED STATES PATENT OFFICE.

JOHN E. HORSTICK, OF NEAR HARRISBURG, PENNSYLVANIA.

LEVER CIDER-PRESS.

SPECIFICATION forming part of Letters Patent No. 372,914, dated November 8, 1887.

Application filed August 3, 1887. Serial No. 246,019. (No model.)

To all whom it may concern:

Be it known that I, JOHN E. HORSTICK, a citizen of the United States, residing near Harrisburg, in the county of Dauphin and State 5 of Pennsylvania, have invented a new and useful Lever Cider-Press, of which the following is a specification.

My invention relates to improvements in portable cider-presses, in which the pressing-beam is operated by a pivoted lever in connection with a reciprocating ratchet-bar and a pawl for engaging its teeth, in combination with a stationary ratchet-bar secured to the under blocking of the sills and engaged by a 10 pawl adapted to lock down the free end of the pressing-beam after the lever has been operated, the ratchets being inserted through a vertical longitudinal slot in the press-head and through two corresponding slots in a block 15 ranged on the press beam over the said slot therein, and having a division-abutment between the slots in said block, against which the ratchet-bars bear when engaged by the pawls, also journaled in said block at a lower 20 level.

My said press has a swinging crane and a lever attachment for handling the cribs, after the pomace has been pressed dry, for removing it from the bed, as will be hereinafter more 25 fully set forth, reference being had to the annexed drawings, in which—

Figure 1 is an isometric view of my press, in which one of the beam-guides has been removed and parts have been broken away of 30 the bed and the cross-brace joining the beam-guides together; Fig. 2, a longitudinal vertical section of the block on the head of the pressing-beam, the section being taken through the slots 35 therein and disclosing the ratchet-bars and pawls in place therein.

In the following description similar reference-letters denote the corresponding parts in the several views.

Letter A denotes the rear hinge-post, to 45 which are bolted the sills B B' by the bolt b, which sills have their front ends supported on the under blocking, C, which is usually formed with legs D D' in trestle form. The lugs P², forming the fulcrul bearings for the lever P, 50 are extended below, through the under blocking, C, as bolts, and are also bolted laterally to

the insides of the sills B B'. Other screw-bolts may also join said sills to the under blocking. Upon the sides of said post A are secured the clips E, through which a rivet or through-bolt, a, hinges thereto, the pressing-beam E, whose front end or head has bolted thereon the block W W', containing therein the pawls m n. Said block is recessed to allow said pawls to swing freely upon the axes or 60 trunnions Q Q', which are journaled in the side walls of said blocks. The block is vertically longitudinally slotted at T T', and has the bulk-head partition M arranged mainly at a higher level than the trunnions Q Q'. The 65 head of the pressing-beam E is correspondingly slotted, to admit freely through it and through said block the ratchet-bars J K, which are arranged with their backs or unnotched edges directed toward each other and working against the partition M when the pawls m n are locked in the notches o of the bars. The 70 partition M thus serves as a guide to keep the said bars nearly parallel to each other and duly spaced apart. The bar J is formed at its 75 lower end into a screw-bolt, J', which is provided with the nuts l, whereby it is secured in the middle portion of the under blocking, C, between the sills B B'. The bar K is given a quarter-turn below and is formed with the 80 wrist K' thereon, through which the coupling-bolt V hinges or pivots said bar to the flanges L on the butt-end of the lever P, as shown. Said lever is pivoted or hinged by the fulcrul bolt P', inserted through the lugs P² and 85 through eyes in the flanges L, so as to bring the axes of the bolts P' and V close together. The journals Q Q' of the pawls m n are extended outside of the block W W', and have inserted 90 through them transversely the winch-form rods g, whose inner ends reach under the lugs h, formed on the exterior of said block, when the pawls are to be held interlocked thereby in said ratchet-bar notches o; or the inner ends of said rods are set on the tops of the lugs h 95 when the pawls are released from said notches, said rods being sprung from their hold under said lugs and adjusted to hold the pawls reversed. The latter adjustment permits the head of the beam E to be elevated after a crib 100 of pomace has been finally pressed. The head of said beam has pivoted thereto the link q,

provided with the eye *r*, into which the pin *p* is inserted when the lever *P* is used for raising said head by these means. The said head is kept elevated and said lever interlocked 5 therewith by the hook *S*, pivoted to said head and hooking into the staple *S'* on the lever. The beam *E* is guided in its rise and descent between the posts *H H'*, as shown and indicated. The cross-brace *x*, which connects said 10 posts *H H'*, limits the descent of said beam in case both said pawls are disengaged inadvertently.

To the post *A* is attached the upright or staff *F* of the crane-arm *F'* by means of the embracing-staple *d'* and a staple or part, *d*, below, having therein an eye, in which works the pin *e*, formed on the shouldered lower end of said staff. To said arm *F'* is joined, by the chain or rod *f*, the lever *F²*, having on its short arm 15 the pendulous hook *f'*, for seizing thereby the crib (shown in dotted lines) containing the pressed pomace for transferring it from the bed *B²* to any receiver therefor on either side or in rear of the press. The flanges *L* on the 20 lever *P* work evenly against the inner faces of

the lugs *P²*, and the wrist *K'* fills the space between said flanges, thus securing said parts in close coupled arrangement.

I do not broadly claim the use of the operating-lever *P*, the stationary holding-bar *J*, and the reciprocating drawing-bar *K*, in connection with the pressing-beam *E*, but only when constructed as set forth and adapted, by the aid of the pawls, so that one man may operate the press alone, and that it shall hold the pressing- 30 beam at all positions in its descent.

I claim—

In a cider-press, the combination, with the vertically-slotted pivoted beam *E*, provided with the block *W W'*, having partition *M*, 40 lugs *h*, and vertical slots *T T'*, of ratchet-bars *J K* in said slots, engaging pawls *m n*, mounted upon said block, with their journals extended beyond the block, and provided with rods *g*, to engage said lugs, operating-lever *P*, and a link 45 connecting said lever with said beam.

JOHN E. HORSTICK.

Attest:

THEOPHILUS WEAVER,
A. BRACKENRIDGE.
